CLAIM

The ornamental design for a cap of a dispensing container, as shown and described.

DESCRIPTION

FIG. 1 is a perspective view of a cap of a dispensing container, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side view thereof;

FIG. 7 is a right side view thereof;

FIG. 8 is a front elevational view thereof, with a larger lid member open; FIG. 9 is a top plan view thereof, with the larger lid member open;

FIG. 10 is a right side view thereof, with the larger lid member open; and,

FIG. 11 is a front elevational view thereof, with a smaller lid member open; FIG. 12 is a top plan view thereof, with the smaller lid member open; and, FIG. 13 is a left side view thereof, with the smaller lid member open.

(Continued)

The broken lines depict portions of the cap of a dispensing container that form no part of the claimed design.
